[54] TRAPEZOIDAL GATE FET DEVICE

[76] Inventors: **Gilbert Hadamard**, deceased, late of Manassas, Va., by Denise L. Hadamard, administratrix, Chemin de la Belloire, St. Jeannet, France

[21] Appl. No.: 920,026

[22] Filed: Jun. 28, 1978

[52] U.S. Cl. 357/23; 357/42; 357/68

[57] ABSTRACT

A trapezoidal shaped FET gate structure is disclosed, having a small end juxtaposed with the drain of the device, to reduce the gate-to-drain capacitance and the Miller effect in an active device or to reduce the pinch-off voltage in an FET load device.
